UNITED STATES PATENT OFFICE.

MELVIN E. DONALLY, OF NEW YORK, N. Y., ASSIGNOR TO AMALIA M. DONALLY, OF SAME PLACE.

BOTTLE-WASHER.

SPECIFICATION forming part of Letters Patent No. 659,167, dated October 2, 1900.

Application filed March 18, 1897. Renewed March 7, 1900. Serial No. 7,747. (No model.)

To all whom it may concern:

Be it known that I, MELVIN E. DONALLY, a citizen of the Dominion of Canada, residing in the city of New York, (Brooklyn,) county 5 of Kings, State of New York, have invented certain new and useful Improvements in Bottle-Washing Machines, &c., of which the following is a specification, reference being had to the accompanying drawings, forming a part 10 hereof.

This invention relates in general to machines for cleaning bottles and other like articles, and more especially to machines commonly known as "shutting-machines," in 15 which the bottles or other articles to be cleaned are reciprocated or shaken to and fro, usually with water or with water and shot in them.

The object which I have had particularly 20 in view has been the production of an improved machine of this class which should be capable of receiving at once a considerable number of bottles or jars or other articles held in a case or frame which can be filled outside 25 of the machine and set into it bodily; but while I have described hereinafter the various features of my invention as applied to such a machine it will nevertheless be obvious that some of such features are capable of application 30 to other machines and in other constructions than that represented, and particularly that the application of the invention is in no wise dependent upon the number of bottles or other articles upon which the mechanism 35 is designed to operate.

In the machine shown in the drawings, which embodies in a practical and desirable form the various features of my invention, the holder, which is adapted to receive and support during 40 operation a number of bottles, is mounted in a frame which is reciprocated by suitable means. A case is provided which can be filled with a number of bottles outside of the machine and set into the holder bodily and removed therefrom bodily with the bottles when the latter are clean. The holder is adapted to rotate in the frame during the reciprocation of the latter, so that the positions of the bottles held thereby are constantly changed, 45 and means are provided to effect the rotation of the holder, which shall not interfere with

the movements of the frame. The said frame is mounted upon its reciprocating carriers so that it can be turned to shift the bottles from the horizontal to a vertical position when the cleaning has been completed and it is desired to empty the water and the shot from the bottles preparatory to removing them from the machine, and when in this position the bottles are rinsed without requiring them to be 55 removed from the machine, which is an important advantage in the use of my machine. Provision is made whereby the turning or tilting of the frame and holder is effected automatically at a predetermined time. Devices 60 are also provided whereby the bottles are automatically released from the holder when the latter is tilted, so that the bottles can be easily and quickly removed.

Other features of the invention will be 70 pointed out hereinafter.

In the drawings, Figure 1 is a side elevation of the machine which I have chosen for illustration of my invention. Fig. 2 is a plan view thereof. Fig. 3 is a detail view, in vertical central section, through the holder and associated parts. Figs. 4 and 5 are detail face views of the two heads hereinafter referred to. Fig. 6 is a detail view of the locking device and its actuating means. Fig. 7 75 is a detail view of the means for controlling the water-supply. Fig. 8 is a detail view of a portion of the stopping mechanism. Fig. 9 is an end view of the removable case, showing the shaft in section.

The various working parts of the machine are supported upon a suitable frame A, the side members of which constitute ways for the reciprocating blocks or carriers hereinafter referred to. A shaft B, having fast 80 and loose pulleys b and b', is mounted in suitable bearings on the frame A and is provided with cams or eccentrics B', by which the desired reciprocations of the bottle-holder can be effected. I have represented said shaft 90 as provided with eccentrics for this purpose, the straps B² being connected by rods b² with the reciprocating blocks C C, which constitute a carrier. For convenience in construction and in operation I prefer to employ two 95 independent blocks or carriers with corresponding actuating devices in place of a rigid 100

frame and a single actuating device, although the precise construction and arrangement of these parts are not material to my invention. I prefer to mount upon the frame spring-buffers D D in the paths of the blocks or carriers C C to diminish the shock at each reciproca-
5 tion.

The blocks C C furnish bearings for the trunnions E' E' of a frame E, which in turn 10 supports the bottle-holder. The said frame E is preferably maintained in a substantially-horizontal position during reciproca-
15 tion and is allowed to tilt or swing into a sub-stantially-vertical position when the bottles supported by the holder have been cleaned and are to be replaced by others. To lock the frame to its reciprocating carrier in a sub-stantially-horizontal position, I may employ a bolt F, which is passed through one of the 20 blocks C and engages the corresponding side of the frame E. I prefer also to provide means whereby the said bolt may be withdrawn automatically after a certain number of reciproca-
25 tions to permit the frame to swing into a vertical position, the frame itself, with the parts carried by it, being preferably over-weighted at one end, so that it shall of itself swing into a vertical position, with the mouths of the bottles downward, as soon as it is re-
30 leased from its carrier. As a convenient means for effecting the withdrawal of the bolt I have provided a slide F', which has fixed thereon a cam f, adapted to engage the roller f' on the bolt F and to withdraw the latter when said slide has been moved a 35 predetermined distance. One side of said slide is formed with a rack f², to be engaged by a pawl f³, which is pivoted on the adjacent block C. A guard-plate f⁴ overlies the 40 rack f², so that said pawl shall engage the rack only as it nears the forward limit of its movement and shall therefore advance the rack the space of one or more teeth, as the case may be. A spring f⁵ is applied to the 45 slide to return it to its initial position when released, and a detent-pawl f⁶ is provided to engage a rack f⁷, which may be formed on the other side or edge of the slide. The said detent f⁶ is held normally in engagement with 50 the rack f⁷ by a spring f⁸ and is also pro-
55 vided with a finger f⁹, which stands in such a position as to be struck by the frame E when the latter swings to a vertical position, thereby releasing the detent and permitting the slide, with its cam, to be drawn back again by the spring to initial position in readiness for operation upon another set of bottles.

The bottle-holder is preferably arranged to 60 rotate within the frame E, and for this pur-
65 pose the holder is mounted upon a shaft G, which is supported in bearings e e on the frame E. As a convenient means of effecting the desired rotation of the shaft G and the holder a wheel G' is affixed to one end of said shaft G, outside of the frame, and has upon its periphery a series of pins or studs g g. Pivotal-
70 ly mounted upon one side of the

frame A and in position to be struck by the pins or studs g g are two arms g' and g², which are disposed one above the other and 75 are inclined in opposite directions. The arm g' rests upon a pin g³, and the arm g² is sup-
70 ported by a finger g⁴, which rests upon the frame. Assuming that the frame E is in its extreme position toward the left in Figs. 1 75 and 2, one of the pins or studs g upon the wheel G' during the next movement to the right of the frame E will pass under and beyond the arm g'. During the next movement of the frame toward the left the same pin or 80 stud will ride up on the arm g', causing a partial rotation of the wheel and shaft, and during the next movement to the right will ride up on the arm g². In this manner and by the engagement of successive pins or studs 85 with the arms g' and g² the rotation of the shaft and holder will be effected as the frame reciprocates, and the positions of the bottles will be changed, so that the cleaning of them will be thorough and complete. 90

The holder comprises in addition to the shaft G a relatively-fixed plate H, which is secured to the shaft G and has holes to register with the mouths of the bottles, and a relatively-movable plate H', which is adapt- 95 ed to support the other ends of the bottles and rotate with the shaft G, although it is free to move longitudinally thereon to a limited extent. To accommodate the holder to bottles of varying heights, the plate H' has, to 100 correspond with each hole h of the plate H, an independent spring-seated cup or plunger h' to receive the foot of the bottle. As represented in the drawings, the plate H' is secured to the shaft G to rotate therewith, 105 with freedom for longitudinal movement, by a pin h², which is fixed in the shaft and enters an elongated slot h³ in the hub h⁴ of the plate H'. An arm or yoke I is connected to the plate H' through its hub h⁴ in such a manner as to permit the free rotation of said plate and is also pivotally connected to the block or carrier C at a point eccentric to the axis upon which the frame E swings. I have represented it as having its ends pivoted 110 upon pins i, which project inward from the blocks C in such positions as not to interfere with the desired swinging or tilting of the frame E. It will now be evident that when the frame is swung or tilted from the horizontal to a vertical position the plate H' will 115 be pushed backward upon the shaft G by reason of the eccentric connection of the arm or yoke I and will therefore release the bottles, so that they can be removed readily and 120 quickly and others put in their places. I prefer to provide light cases or crates J in-
125 dependent of the holder H H' to support the bottles when released by the movement of the plate H' and to facilitate the removal and 130 replacing of the bottles, one case or crate being filled with bottles by the attendant while another lot is being washed and then set bodily into the machine when the crate full

of washed bottles is removed. Each case or crate J preferably comprises a plate J', provided with holes j of a sufficient size to permit the passage through them of the heads of the bottles, and a plate J², provided with holes j' of sufficient size to receive the bodies of the bottles. The two plates are connected at intervals by rods or posts j^2 . In order that each case may be set bodily into the machine, the plates are slotted from one side inward to the center, as at j^3 and j^4 , to straddle the shaft G, and for the purpose of retaining the case in place except when it is to be removed by the operator the width of the slot j^4 in the plate j^3 is somewhat less than the diameter of the shaft G, although the extreme inner portion of said slot is enlarged to the full diameter of the shaft G and is circular to fit said shaft. Somewhat above or to the right of the position which the plate J² occupies during the operation of the machine the shaft G is flattened, as at g^x , so that its thickness shall be the same as the width of the slot j^4 . In placing the case in the machine the plate J² is made to register with the flattened portion g^x of the shaft G and is slipped laterally into place, the shaft G then being vertical, and is then allowed to drop until the plate J' rests upon the plate H of the holder, which movement will bring the plate J² below the flattened portion g^x , preventing any further lateral movement of the case. Inasmuch as each case is laid to suit the bottles to be washed, it will be held against shifting to and fro upon the shaft G when the machine is in operation by contact of the shoulders of the bottles with the plate J' about the holes j . Water is preferably introduced into the bottles during the shaking of the same, and after the shaking and while the bottles are in the machine they are thoroughly rinsed. I have therefore provided the connections which I will presently describe. Mounted upon the shaft G and preferably secured to the frame E is a head K, which has in its face an annular channel k and which also is connected to a suitable water-supply through a pipe k' . A corresponding head K' is also mounted upon the shaft G to rotate with the holder and has in its face an annular channel k^2 , which corresponds to and registers with the channel k of the head K. By a system of headers k^3 and distributing-pipes k^4 water is conducted to the nozzles k^5 , by which it is directed into the bottles through the holes h . A jacket or shot-pocket k^6 , made with many perforations or sieve-like to permit the water to escape freely, especially in rinsing, surrounds the nozzle k^5 to form a receptacle for the shot from the corresponding bottle when the holder is swung or tilted into a vertical position, and another jacket k^7 may, if desired, surround the perforated jacket k^6 , holes k^8 being left in the head k^9 , through which the water may escape. Suitable packing devices are interposed between the two heads K and K' to pre-

vent the escape of water at that point. The pipe k' is preferably a flexible hose and is connected to a stop-cock or valve L, which is secured to the frame of the machine. The stem of the stop-cock or valve is provided with an arm l , which projects into the path of the frame E or of a projection therefrom when the valve is closed. When the bottles have been placed in the machine and the holder is swung from the vertical to the horizontal position, the arm l is struck and the valve opened to permit a small quantity of water to enter the bottles. Then the valve is closed by the operator by turning the arm l to a horizontal position, in which it remains till the bottles have been shaken sufficiently. When the holder swings again to the vertical position, the valve is again opened, and the bottles are thoroughly rinsed by streams of water thrown directly into the bottles through the nozzles while the bottles remain in the machine, thus saving a second handling of the bottles, which is an important feature of the machine. It will be understood, of course, that the shot pass into the perforated jackets or shot-pockets k^6 when the holder is swung to the vertical position.

As it is my desire to make the machine as completely automatic as possible in its action, I have provided means for stopping the shaking automatically at a predetermined time. For this purpose I take advantage of the tilting or swinging of the holder, which, as already described, is tilted or swung from the horizontal to the vertical position at a predetermined time. On one of the trunnions E' of the frame E is secured a wing cam or projection m , which is arranged to strike the shipper-lever M when the frame and holder swing to the vertical position and to operate the same. A bell-crank M' may connect the lever operatively with a shipper-rod M^2 to shift the belt from a fast to a loose pulley in the usual manner or any other equivalent stopping mechanism may be employed in place of the belt-shifter and fast and loose pulleys.

For the purpose of conducting away from the machine the considerable quantity of water which is discharged from the bottles during the washing, and especially during the rinsing, a pan or shield is secured to the frame of the machine below the working parts, as clearly shown in Fig. 1, which catches the water as it is discharged and delivers it to a central trough, from which it may be led away by a suitable pipe.

It will be obvious that in attaining my main object—namely, the production of a machine into which a case of bottles can be set and by which they will be thoroughly washed and also rinsed—the bottle-holder may be supported in various ways to have the desired to-and-fro movement, which may be in a straight line or in the arc of a circle, and that various other changes can be made in the details of construction and arrangement of the me-

chanical devices herein described, wherefore I do not intend to limit my invention to the precise construction and arrangement shown.

I claim as my invention—

- 5 1. In a machine for washing bottles and other like articles, the combination of a main frame having side members, a holder for the bottles or other like articles, a frame in which said holder is rotatably mounted, means for reciprocating said frame, a disk or wheel secured to said holder to rotate therewith with its periphery in proximity to the side members of the main frame and having projecting pins or studs, and a cam or incline supported upon one of said side members in the path of said studs to coöperate therewith, whereby said holder is rotated during the reciprocations of the frame.
- 10 2. In a machine for washing bottles and other like articles, the combination of a holder for the bottles or other like articles, a frame in which said holder is rotatably mounted, means for reciprocating said frame, a wheel secured to said holder to rotate therewith and having projecting pins or studs, a pivoted arm inclined in one direction in the path of said studs, and a second pivoted arm above the first and inclined in the opposite direction, both of said arms being in operative relation with said studs whereby said holder is rotated during the reciprocations of the frame.
- 15 3. In a machine for washing bottles and other like articles, the combination of a holder for the bottles or other like articles, a frame in which said holder is mounted, a carrier in which said frame is mounted to swing, means for reciprocating said frame, a bolt engaging said frame and a relatively-fixed part, a cam to engage and withdraw said bolt and means to move said cam into operative relation with said bolt, whereby, as said cam completes its movement, the frame is released and is permitted to swing with the holder to a substantially-vertical position.
- 20 4. In a machine for washing bottles and other like articles, the combination of a holder for the bottles or other like articles, a frame in which said holder is mounted, a carrier in which said frame is pivoted, means for reciprocating said carrier, a bolt engaging said frame and said carrier, a cam to withdraw said bolt, a slide upon which said cam is mounted, and means to shift said slide progressively as the frame is reciprocated.
- 25 5. In a machine for washing bottles and other like articles, the combination of a holder for the bottles or other like articles, a frame in which said holder is mounted, a carrier in which said frame is pivoted, means for reciprocating said carrier, a bolt engaging said frame and said carrier, a cam to withdraw said bolt, and means actuated by the successive reciprocations of the frame to shift said cam into operative relation with the bolt.
- 30 6. In a machine for washing bottles and other like articles, the combination of a holder

for the bottles or other like articles, a frame in which said holder is mounted, a carrier in which said frame is pivoted, means for reciprocating said carrier, a bolt engaging said frame and said carrier, a cam to withdraw said bolt, a slide upon which said cam is mounted, means to shift said slide progressively as the frame is reciprocated, a spring to return said slide to initial position and a detent to retain said slide against the action of said spring.

7. In a machine for washing bottles and other like articles, the combination of a holder for the bottles or other like articles, a frame in which said holder is mounted, a carrier in which said frame is pivoted, means for reciprocating said carrier, a bolt engaging said frame and said carrier, a cam to withdraw said bolt, a slide upon which said cam is mounted, means to shift said slide progressively as the frame is reciprocated, a spring to return said slide to initial position and a detent to retain said slide against the action of said spring and having a projection in the path of movement of said frame, whereby as said frame is swung or tilted, the detent is released and the slide is returned to initial position.

8. In a machine for washing bottles and other like articles, a holder to receive a number of bottles or other like articles, said holder comprising a relatively-fixed plate, a shaft and a longitudinally-movable plate having spring-seated cups or plungers to receive the ends of the bottles, and means to withdraw said movable plate to release the bottles.

9. In a machine for washing bottles and other like articles, the combination of a holder for the bottles or other like articles, said holder comprising a relatively-fixed plate and a relatively-movable plate adapted to receive the bottles between them, means for supporting the plates, a frame in which said holder is mounted, supports in which said frame is pivoted to swing, and an arm or yoke engaging said movable plate and pivoted to the supports for said frame but eccentrically with respect to said frame.

10. In a machine for washing bottles and other like articles, the combination of a holder for the bottles or other like articles, said holder comprising a shaft, a plate fixed upon said shaft, and a plate held to rotate with and free to move longitudinally upon said shaft, a frame in which said holder is free to rotate, supports in which said frame is pivoted to swing, and an arm or yoke engaging the last-named plate and pivoted to the supports for said frame but eccentrically with respect to said frame.

11. In a machine for washing bottles and other like articles, the combination of a swing frame and a holder for the bottles or other like articles, mounted in said frame, said holder comprising a relatively-fixed plate and a longitudinally-movable plate adapted to receive the bottles between them, means for supporting the plates and connections be-

tween said movable plate and a relatively-fixed part whereby the plate is moved to release the bottles when the frame swings.

12. In a machine for washing bottles and other like articles, the combination of a frame, a holder for the bottles or other like articles, mounted to rotate in said frame, a head secured to said frame and having an annular channel in its face and connected to a water-supply, and a second head having an annular channel in its face and secured to said holder to rotate therewith in contact with the first-named head, and pipes connected to the second-named head to deliver water to the bottles in the holder.

13. In a machine for washing bottles and other like articles, the combination of a reciprocating frame, a bodily-removable, rigid case independent of the frame in which a number of bottles may be placed and set together in the frame and means to secure said case and bottles in said frame.

14. In a machine for washing bottles and other like articles, the combination of a reciprocating frame, a holder supported by said frame and comprising a relatively-fixed plate and a relatively-movable plate, means for supporting the plates, a removable case to receive a number of bottles, and means to move said movable plate to secure or release the bottles and case.

15. In a machine for washing bottles and other like articles, the combination with a reciprocating carrier, of a holder mounted in said carrier and having a central shaft, a case to receive a number of bottles, said case being slotted from one side to the center to be slipped laterally upon said shaft, and means to secure said case and bottles in the holder.

16. In a machine for washing bottles and other like articles, the combination with a reciprocating carrier, of a holder mounted in said frame and having a central shaft with a flattened portion, a case to receive a number of bottles, said case having a slot extended from one side to the center, the central portion of said slot having a width equal to the full diameter of the shaft and the outer portion having a width equal to the thickness of the flattened portion of the shaft, and means to secure said case and bottles in the holder.

17. In a machine for washing bottles and other like articles, the combination of a reciprocating carrier, a swinging frame, a holder mounted in said frame, means to lock said holder in position in the carrier, a bodily-removable, rigid case independent of the holder to receive a number of bottles and means to secure said case and bottles in said holder.

18. In a machine for washing bottles and other like articles, the combination of a reciprocating carrier, a frame mounted to swing in said carrier, a bottle-holder mounted to rotate in said carrier, nozzles supported by said

holder to rotate therewith and to direct a stream of water into each bottle, a sieve-like jacket around each nozzle to receive shot from the bottles, and to permit the water to escape freely, each of said nozzles being located axially with respect to the jacket and the bottle, and means to deliver water to said nozzles.

19. In a machine for washing bottles and other like articles, the combination of a reciprocating carrier, a frame mounted to swing in said carrier, a bottle-holder mounted to rotate in said holder, nozzles supported by said holder to direct a stream of water into each bottle, a sieve-like jacket around each nozzle to receive shot from the bottles, and to permit the water to escape freely, each of said nozzles being located axially with respect to the jacket and the bottle, a water-supply pipe to deliver water to the nozzles, a valve to control said water-supply pipe and means to open said valve.

20. In a machine for washing bottles and other like articles, the combination of a reciprocating carrier, a frame mounted to swing in said carrier, a bottle-holder mounted to rotate in said holder, nozzles supported by said holder to direct a stream of water into each bottle, a perforated jacket around each nozzle to receive shot from the bottles, a water-supply pipe to deliver water to the nozzles, and a valve to control said water-supply pipe having an arm in the path of movement of said swinging frame.

21. In a machine for washing bottles and other like articles, the combination of a reciprocating carrier, a frame, a bottle-holder mounted in said frame, means to reciprocate said frame, stopping mechanism, and devices advanced progressively by the reciprocations of the frame to operate said stopping mechanism.

22. In a machine for washing bottles and other like articles, the combination of a reciprocating carrier, a swinging frame mounted in said carrier, a locking device to hold and release said frame, a bottle-holder mounted in said frame, means to reciprocate said carrier, a stopping mechanism and devices actuated by the frame as it is released and swings to operate said stopping mechanism.

23. In a machine for washing bottles and other like articles, the combination with a reciprocating carrier, a frame mounted to swing in said carrier, a bottle-holder mounted in said frame, a cam carried by said frame, stopping mechanism and a shipper-lever therefor in the path of said cam to be operated thereby.

This specification signed and witnessed this 12th day of March, 1897.

MELVIN E. DONALLY.

In presence of—

W. B. GREELEY,
F. M. EGGLESTON.
